UNITED STATES PATENT OFFICE.

THADDEUS S. GRIMES, OF COLUMBUS, GEORGIA, ASSIGNOR TO LUMMUS COTTON GIN COMPANY, OF COLUMBUS, GEORGIA, A CORPORATION OF GEORGIA.

COTTON TRAMPER.

Application filed June 12, 1922. Serial No. 567,723.

To all whom it may concern:

Be it known that I, THADDEUS S. GRIMES, of Columbus, in the county of Muscogee and State of Georgia, have invented certain new and useful Improvements in Cotton Trampers; and I do hereby declare the following to be a full, clear, and exact description of the invention, such as will enable others skilled in the art to which it appertains to make and use the same.

My object is to provide a tramper head, or follow block, and operating mechanism, and a paddle with its actuating means, the two elements being independently operated to insure their proper relative actions with respect to time under the conditions that may exist. I also provide an improved locking device for controlling the paddle relative to the tramper action. Another object is to provide mechanism for so swinging the paddle that its course will conform to the shape of the lint slide.

In the drawings, Figure 1 is a plan and Figure 2 a front elevation of a tramper embodying my invention. Figure 3 is a vertical section through the tramper. Figures 4 and 5 are details of the paddle actuating mechanism showing two positions of the paddle. Figures 6, 7, 8, 9, show details of the locking mechanism controlling the paddle actuating gears.

The general assembly is of familiar design. As shown in Figures 1, 2 and 3 the main gears 1 are provided with crank pins 2 to which are fulcrumed connecting arms 3 carrying the follow block or tramper head 4. The block is shown with castings 5 in which are journaled wrist pins 6 to which arms 3 are connected. Guide bars 8 are riveted to the castings 5 and extend vertically through grooves 9 formed in the ends of the press boxes 10, 11. These parts substantially constitute the follow block mechanism.

The following has reference to the paddle mechanism.

The shaft 13 upon which the gears 1 are mounted also carries an intermediate gear 14 which I term a "skip gear." It meshes with an idler gear 15 which in turn rotates the gear 16 keyed upon shaft 17. Also keyed upon this shaft 17 are two crank arms

18. They are shown equipped with bearing pins 19 at their ends.

The paddle is designated at 20. It is preferably of wood and is shown secured to links 21. The upper ends of these links are fulcrumed on pins 19 of arms 18, while their lower or outer ends are fulcrumed to pins 22 of swing arms 23 on a shaft 24. This shaft is supported in a bracket 25 as is also the shaft 17. Arms 26, 27, hold the gears in proper position.

Referring now to Figures 4 and 5 the action of the paddle and its operating parts will be understood. As gear 16 rotates, the pins 19 on crank arms 18 describe the circle indicated by the dotted line 28. The pins 22 of arms 23 oscillate in the arc indicated by dotted line 29. In consequence the extremity of paddle 20 travels in the path 31.

As shown in Figure 3, the lint slide 32, at the portion receiving paddle 20, is curved in exact correspondence with the lower part of the path 31 so that the down stroke of the paddle will sweep into the press box and beneath the follow block all the cotton entering the lint slide from the condenser. It should here be observed that the curved lower portion of the chute 31 defines an enlargement or pocket into which a large quantity of cotton can be fed while the paddle 20 is in its raised position as shown in Figure 8. The obvious advantage of this construction is that the feeding of a cotton into the press boxes 10 and 11 will be greatly expedited in a highly efficient and effective manner, it being remembered that the curve of the chute 31 at the site of this pocket exactly corresponds to the path of the paddle 20 so that a "clean sweep" of the pocket or curved portion of the chute will be effected on each working stroke of the paddle. Thus but relatively few actuations of the paddle will be necessary to fill the press boxes.

It is essential that the follow block and paddle properly co-act, one cycle of the block movement to one cycle of the paddle movement, and that their functions be relatively timed in proper sequence. The paddle should reach the end of its sweep stroke and lie in the position indicated in Figures 3 or 4 just as the follow block starts its down-

ward movement. When in this position the paddle constitutes one wall of the press box 10. In order to properly time the action of the paddle I have found the following mechanism to be appropriate and satisfactory.

The gear 14 is interrupted. A blank surface extends substantially half way round its periphery. At this portion it is formed with a flange 34. The idler 15 also has a 10 flange 37 formed with a notch 36. A pawl 35 rides over the flange 37 until it reaches and drops into the notch. At that time the flange 34 will have reached the pawl and begun to bear upon it to hold it in the notch 15 and maintain the gears 15 and 16 locked until the flange 34 passes completely over the pawl and releases it and the toothed surface of gear 14 meshes with gear 15 and imparts to it and gear 16 one complete revolution. Figures 6, 7, 8 and 9, show, respectively, the positions when the gear 15 is locking, fully locked, unlocking and fully unlocked.

As appropriate means for operating the 25 whole mechanism I have conventionally indicated a driven shaft 40 having pinions 41 meshing with the gears 1 and a driving shaft 42 having tight and loose pulleys 43, 44.

30 By the apparatus described, and with proper change of gears, it will be seen that either the follow block function or the paddle action may be varied in speed without affecting the rate of operation of the other. 35 This is of advantage. It allows the number of reciprocations of the follow block to be varied for a given period of time without affecting the speed of the paddle. In this way the action of the block may be 40 varied to suit a larger or smaller volume of cotton entering the lint slide. By changing the diameter of gear 14 the time during which the paddle remains stationary while the block is active may be varied to suit conditions. If the paddle speed is too fast or 45 too slow the cotton will not be properly fed into the press box and will accumulate too much on one side or the other of the box, resulting in a "hollow" or "one sided" bale.

50 I make no claim in this application to the gear lock per se as it forms the subject of a separate application for patent, Serial Number 567,725, filed June 12, 1922.

I claim as my invention:

55 1. In a cotton trumper, the combination with a press box, a follow block and a lint slide leading to said press box, of a paddle movable in said lint slide, means for swinging said paddle on its active stroke in proximity to and in an arc corresponding to the lower wall of said lint slide, and means for periodically locating and maintaining said paddle in a position to close said slide.

60 2. In a cotton trumper, the combination with a press box having an open side, a fol-

low block movable in said press box, and a lint slide entering the open side of said press box, of a paddle movable in said lint slide, and means for holding said paddle stationary against the open side of said press box 70 during the effective action of said follow block.

3. In a cotton trumper, the combination with a press box, a follow block movable therein, means for reciprocating said follow block, and a lint slide leading to said press box, of a paddle movable in said lint slide, a shaft, a gear wheel on said shaft, crank arms also on said shaft and to which said paddle is connected and means for intermittently 75 rotating said gear wheel for periodically locating and maintaining said paddle in a position to close said slide.

4. In a cotton trumper, the combination with a press box, a follow block movable therein, means for reciprocating said follow block, and a lint slide leading to said press box, of a paddle movable in said lint slide, a shaft, a gear wheel on said shaft, crank arms also on said shaft, links fulcrumed on said 80 crank arms and to which said paddle is attached, a second shaft, swing arms fulcrumed at one end on said second shaft and at the other to said links, and means for intermittently rotating said gear wheel for 85 periodically locating and maintaining said paddle in a position to close said slide.

90 5. In a cotton trumper, the combination with a press box, a follow block movable therein, means for reciprocating said follow block, and a lint slide leading to said press box, of a paddle movable in said lint slide, and means for intermittently operating said 95 paddle comprising a gear wheel by which said paddle is carried, a main operating gear, and an intermediate idler, said main operating gear having its toothed periphery interrupted by a smooth surface, a flange on 100 said surface, said idler having a notch in its periphery, and a pawl intermediate the main operating gear and the idler and adapted to be received by said notch and held therein 105 by said flange.

110 6. In a cotton trumper, a press box, a lint slide leading thereto, a feed paddle movable back and forth in the slide, and means for momentarily locking the paddle against movement at the end of its operative stroke.

115 7. In a cotton trumper, the combination with a press box having grooves in its ends, a follow block movable in said press box, and gears for actuating said follow block, of connecting arms fulcrumed to said gears and to said follow block, and guide bars rising from said follow block at points adjacent the connections of the arms therewith and movable in said grooves.

120 8. In a cotton trumper, a press box, a lint slide leading thereto, an oscillatory paddle movable in the slide, means for actuating the 125

paddle, and means for arresting, and locking arrested, the paddle at the end of its operative stroke.

9. In a cotton trumper, a press box, a lint slide leading through the side thereof, a paddle swingingly mounted in the slide and adapted to close the side of the box, means for arresting the paddle in a position for closing the side of the box, and means for operating the paddle and lifting the same 10 on its return stroke.

In testimony whereof I have signed this specification.

THADDEUS S. GRIMES.
